[57] CLAIM

The ornamental design for a combination kniferack,
cutting board and drain, described and shown.

DESCRIPTION

FIG. 1 is a perspective view of a combination kniferack,
cutting board and drain showing my new design;
FIG. 2 is a left side elevational view thereof;
FIG. 3 is a top plan view thereof;
FIG. 4 is a right side elevational view thereof; and
FIG. 5 is a rear elevational view thereof.
The undisclosed bottom view is unornamented.

FIG1.

FIG2.

FIG.3.

FIG.4.

FIG.5.
